UNITED STATES PATENT OFFICE.

LORENZO LANE AND LAURIN D. WOODWORTH, OF YOUNGSTOWN, OHIO,
ASSIGNORS TO THE LANE & WOODWORTH PATENT GLASS ROOFING
COMPANY, OF SAME PLACE.

ROOFING-TILE.

SPECIFICATION forming part of Letters Patent No. 267,904, dated November 21, 1882.

Application filed November 23, 1881. (No model.)

To all whom it may concern:

Be it known that we, LORENZO LANE and LAURIN D. WOODWORTH, citizens of the United States, residing at Youngstown, in the county 5 of Mahoning and State of Ohio, have invented certain new and useful Improvements in Roofing Plates or Tiles; and we do hereby declare the following to be a full, clear, and exact description of our invention, such as will enable 10 others skilled in the art to which it appertains to make and use the same, reference being had to the accompanying drawings, and to the letters and figures of reference marked thereon, which form a part of this specification.

15 Our invention relates to that class of roofing plate or tiles described in Letters Patent of the United States No. 239,104, dated March 22, 1881, held by us as patentees, the same being diamond-shaped, and in which there is a 20 flange or fillet projecting upwardly along the edges above the central line of the plate and a similar flange or fillet upon the opposite side of the plate projecting downwardly below the central line, the plate being curved upward the 25 thickness of the plate on the flange above the central line and curved downward below the central line at the same distance from the central line and by the same curvature as above the central line, so that when placed together 30 with overlapping flanges one exactly fits over the other, thereby preventing the gaping or kicking up that occurs when the plate is not so curved.

In the accompanying drawings, Figure 1 is 35 a plan view of one of our improved tiles. Fig. 2 is a side view of the same. Fig. 3 is a longitudinal section on the line $z z$ of Fig. 1. Fig. 4 is a cross-section on line $x x$. Fig. 5 is a plan view of a half-tile. Fig. 6 is a side view 40 of the same. Fig. 7 is a longitudinal section on line $v v$. Fig. 8 is a cross-section on line $y y$. Fig. 9 is a cross-section of several tiles placed together in their proper position. Fig. 45 10 is a plan view of a roof, showing the tiles in position. Figs. 11 and 12 are detail views.

Our invention consists in the improvements upon said roofing plates or tiles hereinafter set forth and claimed.

In the drawings, A represents the outward 50 surface of the plate with the prolonged flanges,

as above described. The flanges or fillets upon their inner sides are beveled or made at an obtuse angle, as shown at D, with the surface of the plate, so that the base or that part of the flange which joins the plate is broader than its upper edge or side, whereby greater strength is given to the flange than if at right angles with the surface of the plate, and if the plate is made of glass it is much less liable to crack in the process of manufacture, by reason of the 55 more rapid contraction of the glass in the mold, than the mold itself. The ends of the plates most distant from each other are extended with the flanges curving around a space so shaped as to rest over, cover, and conceal with 60 a perfect fit the extensions of the flanges described herein when two are brought together as designed to lie in the roof. Nail-holes perforating the flanges or any part of the plate are dispensed with, and in lieu thereof, and for 65 a means of fastening the plates to the roofing boards or lath at a distance above the central line of the plate great enough to extend beyond the end of the plate immediately below, a half-circle indentation, b, is sunk across the edge of 70 the plate and flange perpendicular to the surface of the plate, and having a beveled-shaped enlargement at the side, designed to be uppermost when laid, so that when the plates are laid in position upon the roofing boards or lath 75 the indentations come together, forming a nail-hole suitable for the use of a rolled nail with a beveled-shaped head countersunk below the surface of the upper edge of the flange. By this means of fastening only one nail is used for 80 each plate, and is sufficient to hold the roof firmly together and to the roofing boards or lath, and hence the roof can be more quickly and cheaply laid. Another great advantage 85 of this means of fastening consists in the fact that if of glass plates with indentations, as above described, can be readily made without danger to the plate, whereas if the plate is perforated with a nail-hole, especially if on the flange, there is great liability to crack on the outward side 90 by contraction of the glass in the process of manufacture, inasmuch as that material in cooling draws toward the center of the piece of ware made. Upon the outward side, A, of the upper edge of the half of the plate used for 95 100

finishing at the comb a flange, *a'*, about the thickness of the plate, extends outward at an angle, so that the pitch of the roof will give to it the effect of a hook. The edges of the zinc or other metal used at the comb are bent underneath this hook, by which the metal at the comb is held firmly to its place and the roof at that part is rendered impervious to water. This part of the plate also has a flange beneath its upper edge thick enough so that when in position it will stand firmly and without tipping upon the roofing boards or lath.

Fig. 11 in drawings represents a lateral view of the half of the plate used at the comb. The letter *a* shows the upper or hook flange, and the letter *b'* the lower flange; and Fig. 12 in drawings shows two of these plates in position upon the opposite pitches of the roof laterally exposed, with the comb metal in place, ready to be bent at its edges under the hooks. The letters *c c* show the plates, and the letter *d* the comb metal. The half *D* of the plate used at the eaves has a flange, *e*, on the under side of the eaves end of the plate and upon the sides covering the space between the roofing-board and the plate caused by the bend in the plate, so that the lower edges of the flanges are on a line with the bottom of the plate that rests upon the roofing boards or lath, preventing tipping. The supplementary plates, or the halves *A'* of the whole plate separated by a line drawn through the center between the most distant points used at the right and left gables, each have a flange, *f*, extending below their longest edges, concealing the space between the plate

and the roofing boards or lath caused by the bend in the plate, notched where required to secure a fit, so that this supplemental plate rests firmly upon the roofing boards or lath and forms a finish that conceals the air chambers or spaces between the plates and that to which they are fastened.

What we claim as our invention, and desire to secure by Letters Patent, is—

1. The diamond-shaped glass tile, having the rounded ends *B*, with beveled part *D* to fit over the adjoining tiles, and provided with semicircular indentations *b*, having a countersink for securing the tiles in place, substantially as described.

2. In roofing-tiles, the flange *a'* at the upper edge of the plates, in combination with the comb of the roof and the comb metal, all arranged substantially as shown and set forth.

3. The combination of a series of glass roofing-tiles, having rounded ends *B*, with beveled part *D*, prolongations *a*, and rounded end *C*, and provided with semicircular indentations *b*, having recessed head for securing them in place, and forming a smooth surface, not exposing any nail-heads, substantially as shown and specified.

In testimony whereof we affix our signatures hereto in the presence of two witnesses.

LORENZO LANE.

LAURIN D. WOODWORTH.
